UNITED STATES PATENT OFFICE.

BENJAMIN BIRKENFELD, OF NEW YORK, N. Y.

AUTOMOBILE SIGNALING DEVICE.

1,352,781.

Specification of Letters Patent. Patented Sept. 14, 1920.

Application filed April 24, 1919. Serial No. 292,435.

To all whom it may concern?

Be it known that I, BENJAMIN BIRKENFELD, a citizen of the United States, residing at New York, in the county of New York and State of New York, have invented certain new and useful Improvements in Automobile Signaling Devices, of which the following is a specification, reference being had therein to the accompanying drawing.

10 This invention relates to improvements in automobile signaling devices of the type comprising an electric lamp with means for attaching the same to the arm of the driver whereby signals may be given at night 15 through movement of the arm to following vehicles.

In devices of this kind, as will be appreciated, conditions demand that the electric lamp employed be relatively small size, that 20 protection for the lamp against breakage be provided, and that the attaching means be simple in construction and readily detachable. An object of the present invention is to provide an improved device of the character 25 referred to in which the lamp while relatively small and provided with protecting means, will, when attached to the arm of the user, stand forth prominently and be clearly visible from vehicles in the rear when the 30 arm is extended.

A further object of the invention is to provide an improved connection between the conducting wires and signaling device so that the stretch of the conductors immediately 35 adjacent to the device are disposed out of the way of the operator, and any strains or pulls on the conductors will not cause the signaling device to be turned or twisted out of position.

40 The invention, with other objects and advantages thereof and the particular construction, combination, and arrangement of parts comprising the same will be understood from the following detail description 45 when considered in connection with the accompanying drawings, forming part hereof and illustrating a preferred embodiment of the invention.

In the drawings,

50 Figure 1 is a top plan view showing a signaling device constructed in accordance with the present invention, applied to the arm of the user, the steering wheel and instrument board of the vehicle being shown in a

general way with the conducting wires leading to a socket on the instrument board.

Fig. 2 is an end elevation of the signaling device on an enlarged scale.

Fig. 3 is a side elevation with the casing for the attaching means removed.

Fig. 4 is a detail view of the guard for the lamp.

While I have illustrated in the drawings a specific embodiment of the invention, it will of course be understood, that minor changes and variations in the particular construction shown, as will appeal to those skilled in the art and falling within the scope of the appended claim may be made without departing from the spirit of the invention.

The construction shown in the drawing comprises an electric lamp socket having a supporting base part 1 and a socket portion 2 of less diameter than the supporting base 75 1. Extending outwardly therefrom seated in the socket portion 2 is an electric lamp, the plug 3' of the lamp and the socket portion 2 being so proportioned in length that the lamp bulb 3 projects a substantial distance outside of the socket. In order to protect the lamp bulb 3 against breakage by contact with the top props or other parts of the vehicle, a guard is provided, the guard being in the form of an open frame arranged 80 over the lamp bulb 3 and mounted upon the support 1. The guard frame is shown as made up of a plurality of metal rods 4, 5, 6 and 7, extending upwardly from the support 1 along side the bulb 3 and being curved 90 inwardly at their outer ends over the top of the lamp bulb 3 and joined together. The rods 4 and 5, are fixedly secured at their lower ends to the support 1. At their upper ends the rods 4 and 5 are rigidly secured together and at the under side provided with a notched portion 8. The other pair of rods have a hinged connection at their lower ends with the frame to be swung outwardly therefrom, and at their outer ends are secured together and fashioned to snap into engagement with the notched portion 8, this construction providing for ready insertion in and removal of a lamp bulb from the socket.

9 designates a ring or band, to which the 105 lamp socket is secured and which is adapted to detachably fit about the fore arm or wrist of a person and support the lamp

socket with the portion 2 thereof and the lamp, bulb 3 standing out from the arm at right angles thereto. The support 1 is suitably secured upon the outer face of the band 5. It is shown located at the side of the band opposite the split or opening in the band. 10 are circuit wires secured to the side of the band 9 opposite the point of location of the lamp socket 2. At the outer 15 ends of the wires is a terminal plug 11 adapted to fit in a socket 12 on the instrument board 13 or other part of the vehicle frame to electrically connect the circuit wires with a battery or lighting circuit on the vehicle. 14 are conducting wires leading from the supporting base part 1 of the lamp socket around one side of the band 9 and connected to the circuit wires 10. The conductors 14 may be secured on the band 9 20 in any desired way. In the drawings they are shown held in position on the band by looping the same thereabout as at 15, 16, and by a wrapping of tire tape 17. 18 is an outer casing preferably of felt or similar material. This affords a good gripping surface and is of substantial thickness to provide a soft protecting layer or pad over the metal band 9, concealing from view the conductors 14, and giving a finished appearance 25 to the device. The casing, which comprises tubular branches fitting over opposing side portions of the band 9 and closed at their outer ends except for a small opening in the end of one for the passage of the circuit 30 wires 10, extends substantially flush with the upper face of the supporting base 1 and is secured in place therearound by stitching or the like.

As illustrated in Fig. 1 of the drawings the band is adapted to be applied to the forearm with the open side of the band facing inwardly and the lamp socket and lamp located at the back of the wrist. The circuit wires 14 connecting with that portion of the band 9 that is located at the inner side of the wrist are entirely out of the way of the

operator, and any pull or strains on the circuit wires 14 in the outward swing of the arm to display the signal will not tend to turn or twist the lamp out of position.

50

It will be observed that in the special construction and arrangement of parts hereinbefore described, the lamp bulb 3 projects a substantial distance outside of the socket portion 2, and is supported to stand out 55 prominently from the arm, at substantially right angles thereto, so that the same is always clearly visible from the rear when the arm is swung out in the usual way to display the signal, the signal being plainly discernible from the rear even though the arm should be twisted palm down, or upwardly, instead of being positioned to face forwardly. The lamp bulb 3 may be plain or of any desired color, preferably the bulb is 60 of a color contrasting with the color of the rear lights customarily used on automobiles, 65

What I claim is:

A signaling device of the kind described comprising a band adapted to be detachably engaged about the forearm, a supporting base mounted to be securely carried on the outer face of the band, an electric lamp socket opening outwardly from the base, an electric lamp having a plug to engage the 70 socket, said plug being of a length to project outside of the socket when engaged therein with the lamp bulb standing out prominently from the forearm entirely clear of and at a substantial distance from the 75 lamp socket, a guard for the lamp consisting of a wire frame secured to said supporting base and extending outwardly therefrom over the lamp bulb, and means for supplying current to the lamp.

In testimony whereof I hereunto affix my signature in the presence of two witnesses.

BENJAMIN BIRKENFIELD.
